MANHOLE COVER

Edward R. Barrett, Detroit, Mich., assignor to
 Gar Wood Industries, Inc., Detroit, Mich., a
 corporation of Michigan

Application April 9, 1934, Serial No. 719,693

10 Claims. (Cl. 220—55)

This invention relates to manhole covers, particularly applicable and used upon tank bodies which are mounted on trucks for transporting liquids. The present invention is concerned with the cover for the filling opening in the manhole cover, and has for its object and purpose the provision of a novel structure which will insure against the striking together and possible breaking of the cooperating releasable connector parts of the filling opening cover and the manhole cover. This will insure against, not only the breaking of such parts which may render the connection of the filling opening cover to the manhole cover ineffective, but also against the possible generation of sparks such as may occur when two pieces of metal strike together. Such complete elimination of any possible spark generation is especially important in connection with tank bodies which carry petroleum products such as gasoline, kerosene and the like.

An understanding of the invention for the attainment of the ends stated as well as many others not at this time specifically enumerated may be had from the following description, taken in connection with the accompanying drawings, in which,

Fig. 1 is a section taken substantially on the plane of line 1—1 of Fig. 2.

Fig. 2 is a plan view of the manhole cover with the filling opening cover thereon.

Fig. 3 is a fragmentary underplan view of the filling opening cover, indicating the manner in which it is mounted on the manhole cover.

Fig. 4 is a fragmentary enlarged underplan view of a portion of the mechanism shown in Fig. 4, with parts in section for better disclosure.

Fig. 5 is a fragmentary transverse section showing the means for interengagingly connecting the filling opening cover to the manhole cover.

Fig. 6 is a fragmentary vertical section through the automatic vent which is mounted on the filling opening cover.

Fig. 7 is a fragmentary vertical section showing the manner in which the manhole cover is detachably secured to the tank, and

Fig. 8 is a fragmentary underplan view of the construction shown in Fig. 7.

Like reference characters refer to like parts in the different figures of the drawings.

The tank body 1 is of sheet metal and may be of any desired size. At its upper side it is provided with an elevated annular rim of metal 2 of the form best shown in Fig. 1 having an in-turned horizontal flange 3 at its upper edge.

This rim 2 is welded or otherwise permanently

secured to the tank body around an opening 4 in the body, and the flange 3 surrounds a manhole opening 5 which is of a size sufficient that if it is desirable to enter the tank body for any purpose a man can do so.

A manhole cover 6 which may be of the shape and form shown in Fig. 2 is located over and rests at its edges upon the flange 3, a suitable gasket 7 being interposed between the edges of the manhole cover and the flange 3. The manhole cover is detachably secured to the rim 2 around the manhole opening. This is done by providing a number of pairs of spaced apart ears 8 at the underside of the manhole cover 6, to each of which the upper end of a rod 9 is pivotally connected. This rod is threaded at its lower end and may be swung to lie between the spaced apart legs 10 of V-shaped sockets formed upon or integral with the ring 2. A nut 11 threaded on the lower end of the rod 9 comes against the underside of the legs 10 releasably securing the manhole cover in place. The manhole cover can be removed by reaching through the filling opening in the cover, hereafter described, and loosening the nuts 11 so that the rods 9 will swing inwardly to a vertical position disconnecting from the legs 10, as is evident. In Fig. 2 four of the pairs of ears 8 and of the rods 9 are indicated. It is, of course, to be understood, that this number may be varied with different dimensions and shapes of the manhole cover 6.

The manhole cover has a centrally located circular filling opening which is surrounded by a downwardly extending annular flange 12 integral with the manhole cover. At the inner side of the flange 12 elongated lugs 13 are cast having undersides on a slight downward incline from one end thereof to the other. Two of these elongated lugs are shown diametrically opposed to each other.

The filling opening cover 14 is of metal and has an annular flange extending over the adjacent edge portions of the filling opening in the manhole cover 6. At the underside of said flange, the cover 14 is equipped with a suitable gasket 15 which is secured to and moves with the cover 14. The filling opening cover 14, as will hereafter be described, is mounted so that it may be turned upwardly and away from the opening to completely uncover the opening. When the cover 14 is brought back to place, gasket 15 strikes the manhole cover 6 and there can be no metal against metal contact insofar as the outer annular flange of the cover 14 and the part of the

manhole cover 6 around the filling opening are concerned.

At the inner side of the filling opening cover 14 downwardly extending lugs 16 are provided, the lower ends of which are turned outwardly so as to pass underneath and bear against the lower inclined sides of the elongated lugs 13. The cover 14 is mounted to turn about a vertical axis so that lugs 16 may be turned to one position beyond one of the ends of each of the lugs 13, as indicated in dotted lines in Fig. 3, and then by turning the cover 14 the lugs 16 may be brought so that their lower outturned end portions bear against the inclined undersides of the lugs 13. A very snug or tight bearing of the filling opening cover against the manhole cover is made.

With my invention there is an insurance that lugs 16 will never strike against the lugs 13 in the movement of the cover 14 from its open to its closed position.

The filling opening cover 14 has a central opening encircled by a downwardly and inwardly extending integral sleeve 17, in which is a suitable vent, indicated as a whole at 18, mounted and housed at its upper portion by part 14a of the cover 14. The structure of the vent specifically is no part of the present invention. The lower member 19 of the vent construction has, as shown in Fig. 6, an outwardly extending flange 19a at its lower end. This member 19 is permanently connected with the cover 14 through a connecting screw 20. Therefore, the vent turns and moves with the cover 14.

An annular groove is provided between the flange 19a and the underside of the cover 14 around the sleeve 17 in which a ring 21 is mounted. The ring at one side has a projecting arm 22 which extends horizontally toward the downwardly extending flange 12 of the manhole cover 6, and is then formed into a downwardly and inwardly extending goose neck 23, the free end of which is pivotally connected to ears 24 cast with and extending downwardly from and below the manhole cover 6. It is evident that the cover 14 may rotate within the ring 21 to different positions and it is further evident that the entire structure including the cover 14, ring 21, arm 22 and goose neck 23 may be turned upwardly and over to the dotted line position indicated in Fig. 1 about the pivotal axis of the pivot connecting the ears 24 with the goose neck 23.

The arm 22 is of substantially channel form having downwardly extending flanges one of which, as shown in Figs. 3 and 4, has an integral downwardly extending stop plug 25 cast therewith. At the outer end 26 of the arm 25 a socket member 27 is cast in which a concave socket of substantially semi-circular shape is made. The member 19 of the vent construction has a short arm 28 extending toward the socket. A yoke 29 is pivoted to the arm 28 and extends toward the socket, terminating in a rod 30 of relatively small diameter, the outer end portion of which is slidably received in a tubular sleeve 31 which has a bearing at one end in the socket at 27. A heavy coiled compression spring 32 is around the rod 30 and a part of the sleeve 31 bearing against a flange 31a on the sleeve and against the shoulder formed on the yoke of the member 29.

When the cover 14 is operatively connected through its lugs with the elongated lugs 13 the parts are in the position shown in Fig. 3. The

filling opening cover 14 is equipped with oppositely extending hand holds 33 (Fig. 2) which may be grasped to turn the cover 14 for the purpose of disengaging lugs 16 from lugs 13. In doing so the spring 32 and the parts 29, 30 and 31 with which it is associated move from the position shown in Fig. 3 to the position shown in Fig. 4. In so doing the spring 32 is compressed until the dead center line is reached whereupon it then operates to work in conjunction with the one turning the filling opening cover and carries the parts to the position shown in Fig. 4 or until stopped by the lug 25. Should the one who is turning the cover 14 to open the filling opening not move the cover far enough, then upon his release of the hand hold arms 33 the cover 14 will then return to its original position and remain engaged with the manhole cover 6. If he moves it to carry the spring 32 and the members associated therewith beyond the dead center line and then releases the cover, the spring will work to move the cover to its extreme position, or until the yoke at 29 engages the stop at 25.

In such position the lugs 16 are carried beyond the ends of the lugs 13 with which they have been previously engaged, whereupon the filling opening cover 14 may be turned, as previously described, to the position indicated in dotted lines in Fig. 1. On closing the cover 14, because of the force of spring 32 holding the cover in the one extreme of its rotative movement, there is always a clearance between the lugs 16 and 13 as the cover 14 comes to closed position. The arms 33 are then engaged and the cover 14 turned so as to engage the lugs with the lugs 13, the spring 32 aiding in tightening such engagement after passing the dead center line as previously described.

The construction described is very practical and useful. The pivotal mounting of the cover 14 is underneath the manhole cover 6 so that no outer lugs or ears are presented which might be broken or damaged. There is insurance against striking lugs 16 against the lugs 13 when the cover 14 is moved from its open to its closed position, making positive that there shall be no damage to or fracture of the connecting parts 13 and 14, and further no generation of sparks which would be extremely dangerous, particularly in connection with tanks carrying petroleum products or other liquids of a like inflammable or explosive nature.

The invention is defined in the appended claims and is to be considered comprehensive of all forms of structure coming within their scope.

I claim:

1. A manhole structure having a filling opening therethrough, a cover for said opening, interengaging means on said cover and on said manhole structure whereby the same may be releasably connected together by turning said cover about an axis of rotation, means for mounting said cover to turn about said axis, means for mounting said mounting means pivotally on the manhole structure whereby the cover may be moved away from said filling opening, and spring means interposed between said cover and the mounting means therefor, operating to prevent striking together of the interengaging means on the cover and the manhole structure when said filling opening cover is moved to closing position after it has been pivotally moved to open position.

2. In a construction of the class described, a manhole cover having a filling opening therein

- provided with a downwardly extending annular ring around said opening, a filling opening cover to close said filling opening, elongated lugs on the inner side of said ring projecting therefrom having inclined inner sides, cooperating lugs on the 5 filling opening cover provided with outwardly turned portions at their lower ends to pass inside the lugs on said ring, means pivotally mounted on said manhole cover at one end thereof and upon which the filling opening cover is mounted to turn about an axis of rotation at the other end whereby 10 the filling opening cover may be moved to open position and also may be turned about said axis of rotation, and means interposed between said mounting means and the filling opening cover, 15 automatically operating to hold the cover in a position when the same is opened, such that the lugs thereon cannot strike against the upper side of the lugs on said ring.
3. In a construction of the class described, a 20 manhole cover having a filling opening, mounting means pivotally mounted at one end on said manhole cover, a filling opening cover rotatably mounted at the other end of said mounting means, interengaging lugs on the two covers whereby on 25 rotating the filling opening cover in one direction it is held against movement to open position and on movement in the opposite direction is moved to disengage said interengaging means on the covers, and spring means interposed between the filling 30 opening cover and said mounting means operating when the filling opening cover is rotated to a predetermined position to move the same rotatively to an extreme position, whereby the interengaging means on the covers are disengaged and held in 35 disengaged relation to each other.
4. A construction containing the elements in combination defined in claim 3, combined with stop means on said mounting means which predetermines the extreme of movement to which the 40 filling opening cover may be moved when disengaging the same from the manhole cover.
5. In combination, a manhole cover having a 45 filling opening therein, a filling opening cover therefor, interengaging means on the covers for releasably connecting the same together on turning the filling opening cover about an axis of rotation, mounting means for the filling opening cover on which the same may turn about said axis of rotation, means for pivotally mounting said mounting 50 means on the manhole cover and a spring interposed between the filling opening cover and said mounting means mounted to have its line of force across the axis of rotation of the filling opening 55 cover and tend to hold the cover in either of two extremes of movement, one at each side of a dead center line wherein the line of force of the spring crosses the axis of rotation of the filling opening cover.
6. In a construction of the class described, a 60 manhole cover having a filling opening therein, mounting means pivotally mounted at one end on and below the manhole cover and at one side of said opening, said mounting means comprising a U-shaped goose neck pivoted at one end on the 65 manhole and at the other end extending upwardly and toward the filling opening and terminating in a substantially horizontal ring located substantially in the plane of the filling opening, a 70 filling opening cover having a downwardly extending cylindrical portion rotatably mounted in said ring, interengaging lugs on the filling opening cover and on the manhole cover and passing one underneath the other on rotation 75 of the filling opening cover in said ring in one direction, and spring means interposed between the lower end of said cylindrical member and the upper end of said goose neck, said spring means mounted and compressed when the filling opening cover is rotated in said ring away from its closed interengaging position with the manhole cover, said compression of the spring means continuing until an intermediate position is reached and thereafter the spring expands and exerts its force to help continue the rotation of the filling opening cover to an extreme position of said filling opening cover wherein the interengaging lugs of the two covers are disconnected, as specified. 5
7. In a construction of the class described, a 15 manhole cover having a filling opening therein, mounting means pivotally mounted at one end on and below the manhole cover and at one side of said opening, said mounting means comprising a U-shaped goose neck pivoted at one end on 20 the manhole and at the other end extending upwardly and toward the filling opening and terminating in a substantially horizontal ring located substantially in the plane of the filling opening, a filling opening cover having a downwardly extending cylindrical member rotatably mounted in said ring, interengaging lugs on the filling opening cover and on the manhole cover and passing one underneath the other on rotation of the filling opening cover in said ring in one direction, 25 an arm extending from the lower end of said cylindrical member, a socket member on said mounting means, a sleeve mounted to turn in said socket, a yoke pivotally connected to said arm and having a rod extending therefrom slidably received in said sleeve, and a coiled compression spring between the sleeve and the yoke, 30 as and for the purposes specified. 35
8. In combination, a manhole cover having a 40 filling opening therein, a filling opening cover therefor, interengaging lugs on the two covers, said lugs on the filling opening cover adapted to pass underneath those on the manhole cover on rotation of the filling opening cover in one direction, means for pivotally and rotatably mounting the filling opening cover, and means for holding the filling opening cover, when rotated in a direction to disengage said interengaging lugs, at an extreme position of movement, wherein said interengaging lugs will not strike against each other on pivotal movement of the filling 45 opening cover to close the filling opening. 50
9. A manhole structure of the class described having a filling opening therethrough, a cover for said opening, interengaging means on said cover and on said manhole structure whereby the same may be releasably connected together, means for operating said interengaging means, means for pivotally mounting the cover whereby it may swing onto or away from said opening, 55 means for holding the interengaging means in inoperative position for the purpose described and means for actuating the last means simultaneously with the operation of the interengaging means. 60
10. In combination, a member, an arm pivoted onto the member, a cover revolvably mounted upon the said arm and adapted to oscillate to either of two extreme positions, and compression 65 spring means interposed between the cover and the arm and mounted to have its maximum compression when the cover is between its extreme positions whereby the cover will be held in either of its extreme positions by the said spring means. 70
